UNITED STATES PATENT OFFICE.

PHILIP LANE SCOTT, OF SYRACUSE, NEW YORK, ASSIGNOR TO SUPER-DIESEL TRACTOR CORPORATION, OF LA PORTE, INDIANA, A CORPORATION OF NEW YORK.

RELIEF MECHANISM FOR FUEL PUMPS.

Application filed June 18, 1918. Serial No. 240,707.

To all whom it may concern:

Be it known that I, PHILIP LANE SCOTT, a citizen of the United States, residing at Syracuse, in the county of Onondaga and 5 State of New York, have invented certain new and useful Improvements in Relief Mechanism for Fuel Pumps; and I do hereby declare the following to be a full, clear, and exact description of the invention, such 10 as will enable others skilled in the art to which it appertains to make and use the same.

This invention relates to improvements in pumps adapted particularly for injecting 15 liquid fuel at high pressure into the working cylinder of an internal combustion engine, where the fuel is vaporized and then ignited by the high temperature of a charge of air which has previously been admitted 20 to the cylinder and compressed to a high degree during the compression stroke of the engine. The liquid fuel is ordinarily supplied through a spray valve, and with the usual types of pumps at present in use, the 25 rate of injection of the fuel decreases rapidly toward the end of the pump stroke, and the amount of fuel delivered is then so small that there is a tendency for drops to form in the fuel spray and at the opening of the 30 spray valve into the combustion chamber of the cylinder.

It is an object of the present invention to provide a pump system having means for 35 suddenly relieving the pressure before too low a rate of pumping is reached, so that the spray valve shall quickly close and cut off any dripping of fuel that might otherwise occur toward the end of the pump stroke.

40 In accordance with the present invention; there is provided on the high pressure side of the fuel pump, a relief valve or equivalent vent controlled by and actuated in timed relation to the other moving 45 parts of the pump, so that as the pump plunger approaches the end of its working stroke the valve will be quickly opened to cause a sudden decrease in the pressure of the oil in the passage leading to the spray 50 valve, with the result that the latter will be quickly closed and the supply of fuel to the combustion chamber of the engine instantly cut off to prevent any excess fuel from dripping through the spray valve.

55 The particular nature of the present in-

vention will appear more clearly from a description of certain preferred embodiments thereof as shown in the accompanying drawings in which Figure 1 represents, chiefly in section, a fuel pump provided with one 60 form of relief valve; Fig. 2 is a portion of the fuel pump of Fig. 1 showing a modified form of relief mechanism, and Fig. 3 is a sectional view of a somewhat different arrangement of the elements of the pump 65 and a different form of relief valve.

Referring to the drawings and particularly Fig. 1, the body 10 of the pump is provided with recesses on opposite sides to receive the usual valves. The suction valve 70 through which fuel is drawn into the pump comprises a plug 11 having a valve seat at 12, and being held in place by an outer plug 13 which is threaded as at 14 for attachment to a pipe leading to the source of fuel supply. A washer 15 between the two plugs insures a tight joint. The valve 16 is normally held against the seat 12 by a spring 17 bearing against a shoulder in the inside 75 of the pump casing.

The discharge valve 18 through which fuel is supplied to the cylinder is held 80 against its seat by a spring 19, the upper end of which bears against a plug 20 screwed into the side of the pump casing, and threaded as at 21 for attachment to a pipe leading 85 to the combustion chamber of the engine. A washer 22 prevents any leakage through the threads of the plug 20.

Between the two valves is the pump chamber 23 within which a plunger 24 is adapted to reciprocate. The plunger 24 passes through a bore in the pump casing 10, and at its outer end carries a roller 25 pressed 90 against a cam 26 by a spring 27. The cam 26 is mounted on a shaft 28 which is actuated from the moving parts of the engine 95 through suitable gearing.

The construction thus far described is one 100 of the usual forms of pumps adapted to supply liquid fuel at high pressure to the cylinder of an internal combustion engine, but in accordance with the present invention there is provided on the high pressure side 105 of the pump, a relief valve which in Fig. 1 is shown as a valve stem 30 slidably mounted in a bore in the pump casing, and provided with a pointed inner end which fits within a conical passageway between the 110 bore and the chamber of the discharge valve.

18. The valve stem 30 is slotted as at 31 to permit the passage of liquid through the relief valve. The outer end of the valve stem 30 is provided with a shoulder 32 fitting 5 within a cavity in the pump casing. A spring 33 engages the shoulder 32, and at its other end bears against a block 34 which is slidably mounted in the bore, but prevented from turning therein by a screw 35 having 10 its inner end fitted within a slot on the side of the block. The outer end of the slideable block is engaged by a cam 36 on a shaft 37 which by means of gears 38, 39 and 40 is driven by and in timed relation with the 15 shaft 28, carrying the cam 26 which controls the operation of the pumping plunger 24.

In the operation of the mechanism described above, the plunger 24 is operated to 20 draw liquid fuel through the suction valve 16 on the outward stroke of the plunger, and force it through the discharge valve 18 on the inward stroke of the plunger, it being understood that the cam 26 is driven in 25 timed relation from the moving parts of the engine to cause the working stroke of the plunger to be performed at the right instant to force the fuel through a spray valve into the combustion chamber of the engine. The 30 shaft 37 carrying the cam 36 which controls the slideable block 34 is so driven with relation to the cam 26 that as the plunger 24 approaches the end of its pumping stroke, the nose of cam 36 will pass off of the end 35 of block 34 and thus relieve the force exerted upon the spring 33 so that the force of the latter upon valve stem 30 will not be sufficient to hold the latter against the pressure that exists in the discharge chamber at this 40 time. The relief valve will thus open and relieve the pressure on the discharge side of the pump. In connection with a pump of the character described, there is at the cylinder, a spray valve through which liquid fuel 45 is injected into the combustion chamber, and the release of pressure between this valve and the discharge valve 18 will cause the spray valve to be quickly closed, cutting off any dripping of fuel into the cylinder. The 50 relief valve 30 will remain open until the nose of cam 36 again engages the end of sliding block 34 to again put the spring 33 under compression sufficient to hold the relief valve closed against the pressure produced in the 55 chamber of the discharge valve 18 on the next working stroke of the pump plunger. A fuel supply pump of the general type shown in Fig. 1 may be operated without the discharge valve 18, the spray which controls 60 the admission of fuel into the combustion chamber being used as an equivalent of the discharge valve. In this case the relief valve may be located at any point beyond the suction valve 16, because it is then only 65 necessary to relieve the pressure in the sys-

tem between the suction valve 16 and the spray valve to cause the latter to close quickly to prevent leakage into the combustion chamber.

Figure 2 shows a modification of the invention in which a plunger 45 is substituted for the valve stem 30 of Figure 1. The plunger 45 is slidably mounted in a bore in the pump casing, but has an oil-tight fit therein. The outer end of this plunger is provided with an enlarged head 46 adapted to be engaged by a cam 47 corresponding in function to the cam 36 of Fig. 1. The enlarged head 46 is formed at its inner end with a shoulder 49 serving as an abutment for one end of a spring 50 the other end of the spring being retained by a plug or nut 51, screwed into the casing.

In this modification of the invention, as the pump plunger 24 approaches the end of its pumping stroke, the nose of cam 47 passes out of engagement with the head 46, thus permitting the fluid pressure acting upon the inner end of plunger 45 to force the latter outwardly against the compression of spring 50, it being understood that this spring is so adjusted that it will yield under the pressure existing on the discharge side of the pump, as the pump plunger approaches the limit of its pumping stroke. 95 Outward motion of plunger 45 will tend to create a vacuum on the discharge side of the pump, which will cause a sudden decrease of pressure in the liquid on this side of the pump, with the result that the spray valve 100 will be closed quickly to prevent any leakage therethrough.

If the plunger shown in Fig. 2 is used instead of the valve 30 of Fig. 1, it is necessary that the discharge valve 18 be eliminated, or if it is retained, means should be provided for holding it open at the beginning of the suction stroke of the pump plunger. If the discharge valve should be left in the pump, the plunger 45, as it is returned to its original position by cam 47, would in itself act as a pump and tend to force liquid through the spray valve. If the discharge valve 18 is removed, then the pump chamber 23 and the chamber with 110 which the plunger 45 is associated, are in free communication, and the effect due to the return of the relief plunger 45 to its inward position would be compensated for by the simultaneous withdrawal of the pump plunger on its suction stroke, so that there will be no tendency for liquid to be forced 115 through the spray valve during the return stroke of the relief plunger.

Fig. 3 shows a modification of the invention in which the relief mechanism is associated directly with the pump chamber instead of with a chamber communicating with the latter as in the case of Figs. 1 and 2. In Fig. 3 the pump plunger, the inlet 125

valve and the discharge valve are substantially the same as the corresponding parts of Fig. 1, except that the pump plunger 24' has a tapered end as at 55, and the stem of 5 the discharge valve 18' is provided with a screw 56 adapted to be engaged by the plunger 24' as the latter approaches the end of the pumping stroke. In this figure, the relief mechanism comprises a valve stem 57 10 slidably mounted in a tubular member 58 inserted in a bore in the pump casing and communicating with the pump chamber 23'. The inner end of the valve stem is tapered to fit a correspondingly formed valve seat 15 at the inner end of the tubular member 58. This tubular member is held in place against a washer 59 by a plug 60 provided with a bore to receive the enlarged end 61 20 of the valve stem, and a spring 62 which bears against this enlarged end, and at its 25 other end is held in place by an adjustable plug 63. The valve stem 57 is provided with one or more longitudinal grooves 64 to permit the discharge of liquid from the pump 28 chamber when the valve stem is forced outwardly by engagement of the pump plunger 24' with a screw 65 adjustably mounted in the inner end of valve stem 57.

The force of the spring 62 is such that it 30 holds the valve 57 upon its seat at the inner end of the tubular member 58 against the pressure that exists during the pumping stroke, but when the pump plunger 24' approaches the end of this stroke, it engages 35 the screw 65 and forces the valve stem 57 outwardly against the effect of spring 62, thus causing the pressure in the pump chamber to be instantly relieved. At the same time that the inner end of the pump plunger 40 engages the screw 65, the cylindrical part of the plunger will pass under the screw 56 of the discharge valve 18' and hold this valve open while the pressure is being relieved by the opening of the relief valve. Were it 45 not for this arrangement, the discharge valve 18' would close as soon as the pressure in the pump chamber was relieved, and leakage of liquid through the spray valve might not be avoided. As soon as the pump 50 plunger begins its suction stroke, it moves out of engagement with the screws 56 and 65, thus permitting the discharge valve and the relief valve to close.

I claim:

1. In a fuel injecting system for internal combustion engines having a pump supplying liquid fuel under high pressure to an injection valve to open the valve and force the fuel into the combustion chamber, the 55 combination of a vent between the pump and the injection valve, means for closing said vent during the injection stroke of the pump, and means for releasing said closing means near the end of the injection stroke 60 to permit said vent to be opened to abruptly

diminish the pressure of the liquid fuel at the opening into the combustion chamber and cause a sudden closing of the injection valve to prevent dripping of the fuel.

2. In a fuel injecting system for internal 70 combustion engines having a pump supplying liquid fuel under high pressure to an injection valve to open the valve and force the fuel into the combustion chamber, the combination of a vent between the pump and the injection valve, a closure for said vent, means for holding said closure in vent-closing position during substantially the entire injection stroke of the pump, and means for releasing said holding means near the end of 80 the injection stroke to permit said closure to open the vent to abruptly diminish the pressure of the liquid fuel at the opening into the combustion chamber and cause a sudden closing of the injection valve to prevent 85 dripping of the fuel.

3. In a fuel injecting system for internal combustion engines having a pump supplying liquid fuel under high pressure to an injection valve to open the valve and force 90 the fuel into the combustion chamber, the combination of a vent between said pump and said injection valve, means for closing said vent, means for holding said closing means in vent closing position against the 95 pressure of the fluid between said pump and said injection valve during substantially the entire injection stroke of the pump, and means for releasing said holding means to permit the pressure of the fluid to open the 100 vent near the end of the injection stroke to cause an abrupt diminution of pressure at the opening into the combustion chamber and produce a sudden closing of the injection valve to prevent dripping of the fuel. 105

4. In a fuel injecting system for internal combustion engines having a pump supplying liquid fuel under high pressure to an injection valve to open the valve and force the fuel into the combustion chamber, the 110 combination of a vent on the high pressure side of the pump, means for closing said vent against the fluid pressure produced by said pump, during its injection stroke, and means under the control of said pump for 115 actuating said vent closing means to open the vent near the end of the injection stroke of said pump to abruptly diminish the pressure of the liquid fuel at the opening into the combustion chamber and cause a sudden closing of the injection valve to prevent 120 dripping of the fuel.

5. In a fuel injecting system for internal combustion engines having a pump supplying liquid fuel under high pressure to an 125 injection valve to open the valve and force the fuel into the combustion chamber, the combination of a vent on the high pressure side of the pump, means for closing said vent against the fluid pressure produced by 130

said pump during its injection stroke, and means adjustably associated with said closing means and adapted to be engaged by the plunger of the pump for actuating said vent closing means as the plunger approaches the end of its injection stroke to abruptly diminish the pressure of the liquid fuel at the opening into the combustion chamber and cause a sudden closing of the injection valve to prevent dripping of the fuel.

6. In a fuel injection system for internal combustion engines, having a fuel pump provided with suction and discharge valves and a piston for forcing fuel through the discharge valve into a conduit leading directly to a fuel injection valve through which fuel may be supplied to the combustion chamber of the engine, the combination of a vent communicating with the conduit, means for closing the vent during the injection stroke of the pump, and means for releasing the closing means near the end of the injection stroke to permit said vent to be open to abruptly diminish the pressure of the fuel in the conduit to cause a sudden closing of

the injection valve to prevent dripping of the fuel.

7. In a fuel injection system for internal combustion engines, having a pump supplying liquid fuel under high pressure to an injection valve to open the valve and force the fuel into the combustion chamber, the combination of a vent on the high pressure side of the pump, a closure for said vent, a spring for holding said closure in vent closing position against the fluid pressure produced by the pump during its injection stroke, and means operable in timed relation with the pump for relieving the tension of the spring near the end of the injection stroke of the pump to permit the pressure of the fuel to act upon the closure to open the vent to cause an abrupt diminution of pressure at the opening into the combustion chamber and produce a sudden closing of the injection valve to prevent dripping of the fuel.

In testimony whereof I affix my signature.

PHILIP LANE SCOTT
